EXTENSION TABLE

William Chrobersky, Brooklyn, N.Y.

Application May 12, 1958, Serial No. 734,552

2 Claims. (Cl. 311—16.5)

This invention relates generally to tables. More particularly, the invention has reference to an extension table, designed for being collapsed to a relatively small size, while still being extendable, whenever it is to be used, to a substantial size.

An object of importance is to provide an extension table of the character stated that will be highly compact, and will take up a minimum amount of floor or closet area when it is not in use.

Another object is to so form the table that when collapsed, it will be an attractive item, so that it can be left in view.

Another object is to provide a collapsible table of the character described that will be so formed as to be extendable to a very large size, considering the size thereof when it is collapsed.

Another object is to provide a collapsible table which will have all its relatively moving parts concealed from view when the table is not in use, thus to further increase the attractiveness of the device.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of an extension table according to the present invention, in its collapsed or folded condition.

Fig. 2 is a front elevational view thereof.

Fig. 3 is a top plan view of the table, the table being shown in full lines in its folded condition and in dotted lines in its unfolded or operative condition.

Fig. 4 is an enlarged, vertical sectional view substantially on line 4—4 of Fig. 2.

Fig. 5 is a view on the same scale as Fig. 4, taken substantially on line 5—5 of Fig. 4.

Fig. 6 is an enlarged, transverse sectional view through the front legs, substantially on line 6—6 of Fig. 4.

Fig. 7 is a view on the same scale as Fig. 6, through one of the rear legs, taken on line 7—7 of Fig. 4.

Fig. 8 is a still further enlarged fragmentary perspective view showing the hinge connection of the two forwardmost leaves.

Fig. 9 is a transverse sectional view through the table, on substantially the same scale as Fig. 4, taken on line 9—9 of Fig. 4.

Fig. 10 is a view on the same scale as Fig. 9, comprising a horizontal section through the table slide, substantially on line 10—10 of Fig. 9.

Fig. 11 is a view looking upwardly at the table slide, from the line 11—11 of Fig. 9, on the same scale as Fig. 9, with the table slide in a fully folded condition.

Fig. 12 is a view like Fig. 11, portions being broken away, showing a fragmentary part of the table slide in an unfolded or extended position.

Fig. 13 is a detail view, the scale being enlarged still

2

further, showing one of the hinges connecting the table leaves, as seen from line 13—13 of Fig. 4.

Fig. 14 is an enlarged, fragmentary side elevational view of two of the table leaves in an unfolded condition, illustrating the hinge of Fig. 13.

Referring to the drawings in detail, designated generally at 10 in the several figures of the drawing is an extension table according to the present invention. This includes side walls 12, which have rectangular rear portions 13 integral at their lower ends with forwardly projecting front portions 14 that are substantially lower in height than the rear portion, so that the side walls may each be considered as having a substantially L-shaped configuration when the table is viewed from the side, as clearly seen in Fig. 1.

Referring to Fig. 4, the table has a top wall 16 connected between the upper ends of the side walls, and a back wall 18 which closes the table at the back and extends the full height of the rear portions 13 of the side walls. Connected between the side walls and projecting forwardly from the lower end of the back wall 18 is a bottom wall 20, which terminates short of the front edges of the side walls.

It may thus be seen that the table includes a cabinet-like housing comprised of the side walls, top wall, back wall, and bottom wall. Said housing also includes a front defined by doors 22 which are hinged at 24 to the side walls, and are swingable between the full line closed position and open, dotted line position shown in Fig. 3. The doors need to be opened only when the table is being extended or retracted. Thereafter, the doors can be kept closed. Thus, when the table is extended to the dotted line position shown in Fig. 3, the doors can be immediately closed after the extension operation. They may be left closed until such time as the table is to be collapsed to its normal Fig. 4 condition.

The doors have pulls or handles 26 in a typical embodiment of the invention.

The housing is supported upon rear legs 28 which are affixed at their upper ends to the bottom wall 20, and which as shown in Fig. 7 are of diamond-shaped or rhomboidal cross section.

At the front corners, the housing has blocks 30, which are fixedly secured to the inner surfaces of the forwardly projecting portions of extensions 14 of the side walls. Blocks 30 are integral or otherwise rigid at their lower ends with front legs 32 of the housing.

As will be noted from Fig. 6, each leg 32 is of isosceles-triangular cross section, that is, each leg 32 is half the area of a leg such as the rear leg 28. The purpose of this arrangement will be described in greater detail hereafter.

Generally designated at 34 is the extension leaf assembly, designed to be extended forwardly out of the housing, and normally collapsed within the housing as shown in Fig. 4. In using the term "leaf assembly," it will be understood that this term is intended to embrace not only the actual leaves of the assembly, but also all other movable portions. These include the table slide, the front end wall, and those front legs that are moved forwardly with the front end wall.

Thus, the assembly 34 includes, at the front end thereof, a front wall 36. This extends transversely of the table, for substantially the full width thereof (see Fig. 2). Front wall 36 is extended between the extensions 14 of the side walls as shown in Fig. 2, being normally flush with the front edges of the side walls. The side walls are slightly higher than the front wall 36. Fixedly secured to the rear surface of the front wall, as seen in Figs. 5 and 9, are blocks 38, which are in side-by-side relation to blocks 30 when the assembly 34 is in its collapsed condition. Integral with the blocks 38 are movable front

legs 40. These are of triangular cross section, being oppositely but identically formed to the adjacent legs 32 (see Fig. 6). As a result, each leg 32 and its adjacent leg 40 form a front leg assembly at each of the front corners, generally designated 41. Each front leg assembly is of rhomboidal or diamond-shaped cross section, matching the cross-sectional shape of the rear legs 28. However, when the assembly 34 is pulled forwardly to extend the table, each leg 40 moves forwardly out of its side-by-side relation to the adjacent leg 32.

This provides an attractive appearance to the table, when it is collapsed. There is little indication of the fact that the legs 40 move out of side-by-side relation to the legs 32, from their normal positions beside the legs 32, said normal positions being shown in Fig. 2 and in Fig. 9.

Fixedly secured to the top edge of the wall 36 is the front edge portion of a forwardmost leaf 42. Leaf 42 is horizontally disposed, and is exposed in front of the doors 22 when the table is in its collapsed condition.

The forwardmost leaf 42 is hingedly connected to a second leaf 44 by means of a flat hinge 46 (see Figs. 4 and 8). The leaf 44 is vertically disposed when collapsed, directly in back of the doors 22. It is slightly smaller in respect to the distance between its front and back edges, than is the leaf 42 or the remaining leaves 48 of the table.

Hinges 46 are flush hinges, and are arranged not to open beyond the ninety degree angular relationship of its hinge leaves shown in Figs. 4 and 8. When the table is extended, leaf 44 of course moves into coplanar relationship to leaf 42, and at this time, the hinge leaves 47 become horizontally aligned rather than in their right-angular relationship shown in Figs. 4 and 8.

Behind the second leaf 44 are leaves 48, of which there may be any desired number. In the illustrated example, there are thirteen leaves 48, but this number could be made either smaller or larger, as desired. The rearmost leaf 48 is hingedly connected at 50 to the back wall 18.

Hinges 52 are used to connect the leaves 48 to each other. These hinges are of a well-known, commercially available type known as "Soss" hinges. Such a hinge appears as in Fig. 13. It is so designed that members connected thereby may be moved from side-by-side, face-contacting relationship into a coplanar relationship, with the hinges being completely concealed as shown in Fig. 14.

As will be noted, that leaf 48 which is immediately in back of the leaf 44 is connected by a Soss hinge 52 at its upper edge to the upper edge of the folded leaf 44. Then, the next leaf 48 is connected to the one hinged to leaf 44, by means of Soss hinges 52 located at the lower edges of the leaves. In other words, the Soss hinges alternate between the top and bottom edges of the leaves. Thus, the leaves are all connected accordion-fashion, being hingedly connected to each other and being foldable to a position in which they are all in face-to-face contact in vertical planes, as shown in Fig. 4. When the extension table is extended, then the leaves 44 move into a coplanar relationship, as shown in Fig. 3.

Generally designated at 54 is a table slide, designed to prevent sagging of the extended table. Table slides are known in and of themselves, and any of various conventional table slides may be employed. It is understood that according to the number of leaves and the distance that the table is capable of being extended, the table slide may vary and may have any number of relatively slidable members. In the illustrated example, the table slide 54 includes eight side-by-side members. These are connected for relative sliding movement in the direction of their lengths between the fully collapsed condition shown in Fig. 11 and an extended position shown in Fig. 12.

The table slide has a plurality of members 56, all of which are similar to one another, and has one member 58, which is identical to the members 56 except for hav-

ing an upwardly opening longitudinal channel 59 (see Fig. 5). The lower Soss hinges 52 have projecting portions when the leaves 48 are collapsed as in Fig. 4, and these projecting portions extend downwardly into the channel 59.

In the illustrated embodiment, there would be two identical table slide assemblies 54, transversely spaced as shown in Fig. 2, so as to provide support at both sides of the extended table.

10 Since these assemblies 54 are identical to each other, the description of one will suffice for both.

Referring to Figs. 9-12, each member 56 has at one side a longitudinal tongue 61, slidably engaged in a complementary, longitudinal side groove 63 of the next adjacent member 56. As a result, each member 56 is connected to similar members disposed at opposite sides thereof, for relative longitudinal movement. Normally, in the collapsed condition of the table, all the members are coextensive, as shown in Fig. 10. At one side of the assembly 54, there is a member 56 that is fixedly secured at its forward end to the front wall 36. At the opposite side of the assembly 54, a member 56 is secured at its rear end to the back wall 18.

Projecting laterally from one side of each member 56 or 58 is a stop block 62, provided at one end of each member. At the opposite end of the member there is a stop block or abutment 64.

It will thus be seen that the member 56 that is fixedly connected to the wall 36, when shifted forwardly, will slide relative to the next adjacent member 58. Then, the block 62 of the forwardmost member 56 comes into engagement with the block 64 of the next adjacent member 58. Member 58 is then pulled forwardly, and in turn its stop block 62 engages the block 64 of the next adjacent member 56. This continues over the full length of the table slide, until the table slide is fully extended simultaneously with movement of all the leaves 48, to their fully extended position.

In this way, when the table is pulled out to extend the same, as for example to the dotted line position of Fig. 3, the table slides automatically extend, remaining in supporting relation to the leaves, which unfold to extend the table.

Referring now to Fig. 4, alternate leaves of the table are provided at one side with small side openings or recesses 66. Engageable in any selected recess 66 is a drop or latch pin 68. This may be moved through any of a plurality of openings 70 formed in one of the walls 12 (see Fig. 1) in registration with openings 66. Pin 68 is carried by a chain 72 disposed exteriorly of the housing, said chain being secured to an anchoring plate 74 that is attached fixedly to the side wall 12.

Due to this arrangement, it will be seen that when the table is fully collapsed, the pin 68 can be engaged in the forwardmost opening 66, being projected through the forwardmost opening 70 as shown in Fig. 1. This locks the leaves 48 against movement to extended positions.

Assuming that the table is to be extended, one removes the pin 68 and permits it to hang down at the side of the table, if all the leaves 48 are to be moved to horizontal, extended positions. The doors 22 are opened, and by grasping the front wall 36 and moving the same forwardly, one can pull the table to an extended position. First, leaf 44 moves into coplanar relation with leaf 42, and then successively following leaves 48 unfold and move into a horizontal plane, all supported upon the now extended table slide assemblies 54.

After the table has been fully extended, the doors 22 are closed and the table is ready for use.

If one were to desire to extend the table only for part of its fully extended length, one can readily limit the extension of the table beyond a predetermined point. This is done by insertion of the pin 68 in a selected opening 70. If, for example, the pin 68 were inserted through that opening 70 which is disposed at the direct middle

of the row of openings 70 appearing in Fig. 1, it would engage in a corresponding opening 66. Therefore, in this situation only the six forwardmost leaves 48 would move to horizontal position, together with leaf 44. All the leaves 48 from this point to the rearmost leaf 48, including the one in which the pin 68 is engaged, are locked in their collapsed, vertical positions.

Thus, one can select the degree to which the table is to be extended, merely by insertion of pin 68 in any of the various openings 70. The lock pin arrangement, thus, serves a highly desirable purpose. Not only does it prevent the table from being extended any more than is absolutely desired, but also, when the table is in its fully collapsed condition the lock pin holds all the leaves in their locked relation. This prevents their accidentally shifting from their proper, vertical, collapsed positions.

As will be seen, the table has various beneficial features. When collapsed, it occupies a very small floor area, and comprises an attractive piece of furniture, with all moving parts being completely concealed. When, however, it is desired to use the same as a table, it can be extended to provide a quite large table area. Further, this area can be selected by the user in the manner described above with reference to the pin 68, so that the area is of a selected, adjusted size. When the size has been selected by insertion of pin 68 in a selected one of the openings 66, one proceeds to extend the table without fear that it will be over-extended beyond the selected size. Further, the extension of the table is achieved merely by forward movement of the front part of the table leaf assembly 34, and there is no need for one having to operate complicated linking assemblies, special lock devices, etc. One need not operate any devices that are under the table or at some other inconvenient or relatively inaccessible location.

While I have illustrated and described the preferred embodiment of my invention, it is to be understood that I do not limit myself to the precise construction herein disclosed and that various changes and modifications may be made within the scope of the invention as defined in the appended claims.

Having thus described my invention, what I claim as new, and desire to secure by United States Letters Patent is:

1. An extension table comprising a housing, and an extension assembly including a series of table leaves hingedly connected to each other for relative swinging movement about horizontal axes, said leaves collapsing accordion-fashion within the housing and being extendable from the housing into a common horizontal plane, said extension assembly further including at least one

45

50

table slide assembly supportably underlying said leaves in the extended positions of the leaves, the housing including doors at the front thereof in back of which the leaves are disposed in their collapsed condition, said leaves when collapsed being disposed in vertical planes, in face-to-face contact with each other, said extension table further including lock means carried by the housing adapted for lockably engaging a selected one of said leaves against movement relative to the housing from its collapsed condition, whereby to permit extension only of a selected number of said leaves, said locking means including a pin, the housing and some at least of said leaves having openings registering in the collapsed positions of the leaves, for extension of the pins through a selected pair of registered openings of the housing and leaves.

2. An extension table comprising a housing, and an extension assembly including a series of table leaves hingedly connected to each other for relative swinging movement about horizontal axes, said leaves collapsing accordion-fashion within the housing and being extendable from the housing into a common horizontal plane, said extension table including front and rear legs on the housing, the extension assembly including a pair of front legs disposed in side-by-side relation to the first-named front legs in the collapsed positions of the leaves, said extension assembly further including a forwardmost leaf disposed in horizontal position in the retracted position of the extension assembly and secured to the second-named front legs, at the forward end of said series of first-named leaves, to the horizontal leaf and being hingedly connected at the rear end of said series to the back wall of the housing, said first-named leaves all being disposed in vertical positions when in their collapsed condition, the rearmost one of said series of first-named leaves having a bottom edge hingedly joined to the housing at the back of the housing, downwardly from the uppermost portion of the housing, said first-named leaves being connected to one another by hinges wholly concealed in the extended positions of the first-named leaves, said extension table further including a latch pin releasably engaging selected ones of the first-named leaves in the collapsed positions of said first-named leaves.
